INVENTOR.

UNITED STATES PATENT OFFICE.

HARRY R. HOLDEMAN, OF LOS ANGELES, CALIFORNIA, ASSIGNOR TO THE J. M. FELDMAN CO. INC., OF LOS ANGELES, CALIFORNIA.

DESIGN FOR A PIERCED-EFFECT LIGHTING-FIXTURE PANEL.

Application filed December 19, 1927. Serial No. 24,522. Term of patent 3½ years.

To all whom it may concern:

Be it known that I, HARRY R. HOLDEMAN, a citizen of the United States, residing at Los Angeles, in the county of Los Angeles and State of California, have invented a new, original and ornamental Design for Pierced-Effect Lighting-Fixture Panels, of which the following is a specification, reference being had to the accompanying drawing, forming part thereof.

The figure is a plan view of a pierced effect lighting fixture panel showing my new design.

I claim:

The ornamental design for a pierced effect lighting fixture panel as shown.

HARRY R. HOLDEMAN.
